UNITED STATES PATENT OFFICE.

LOUIS W. WITRY, OF WATERLOO, IOWA, ASSIGNOR TO WATERLOO GASOLINE ENGINE COMPANY, OF WATERLOO, IOWA.

POSITIVELY-ACTUATED LUBRICATING DEVICE.

1,183,153.

Specification of Letters Patent.

Patented May 16, 1916.

Application filed July 19, 1915. Serial No. 40,682.

To all whom it may concern:

Be it known that I, LOUIS W. WITRY, a citizen of the United States of America, and a resident of Waterloo, Blackhawk county, 5 Iowa, have invented certain new and useful Improvements in Positively-Actuated Lubricating Devices, of which the following is a specification.

My invention relates to improvements in 10 positively actuated lubricating devices, and the object of my improvement is to provide a lubricating apparatus more particularly designed for the lubrication of the bearings of engine crank-shafts or the like, wherein 15 the lubricating material is forced through the delivery devices of the apparatus in the proper amounts, and is then re-collected for re-use by suitable means being a part of the apparatus. This object I have accomplished 20 by the means which are hereinafter described and claimed, and which are illustrated in the accompanying drawings, in which:

Figure 1 is a vertical transverse section 25 of the crank-casing of a crank-shaft and through my improved pump and lubricating device connected therewith. Fig. 2 is a longitudinal vertical section of the parts shown in said Fig. 1, with part of the crank-casing 30 broken away.

Similar numerals of reference denote corresponding parts throughout the several views.

The casing 29 has bearing-openings for a 35 rotatable shaft 30 provided with the cranks 31, and other bearings for the ends of a cam-shaft 32 located to the rear of the shaft 30 and about in the same horizontal plane, and parallel therewith. The cam-shaft has a 40 cam-wheel 33 fixedly mounted thereon and adapted to actuate the contacting end of a medially-pivoted rock-lever 34, pivoted at 35, and whose other end is pivoted at 36 to the upper end of a pitman 8. The lower 45 end of said pitman is hemispherical and seated movably in a concave seat or socket in a block 7, the latter fixed on the plunger or stem of a solid piston 5 which plays in the pump-cylinder 3. A compression-spring 50 6 is coiled about said stem and engaged between the block 7 and the top of the pump-cylinder and therefore tends to yieldingly push up the pitman and the arm of the rock-lever pivoted thereto to keep the other end

of the lever in working contact with the 55 cam-wheel.

The cylinder 3 forms part of a casting 2, the upper part of which together with the cylinder being passed through and fitted in a bearing-seat 37 in the bottom of said casting. Said casting has a channel 9 therein in communication between the pump-chamber 4 and the interior of the casing, said channel being controlled by a ball check-valve 11, and the end of the channel which is located 60 within the casing being protected by a tubular structure of netted fabric to serve as a strainer for a supply of oil which is kept permanently in the bottom part of the 65 casing.

Another channel 12 is provided in said casting, and has an orificed screw-plug 15 inserted in its outer end, said plug communicating with a stand-pipe 16 while the other end of said channel communicates with the 75 chamber 4, the entrance being controlled by means of a ball-valve 13 kept yieldingly in position by means of a small relatively weak coiled spring 14. The stand-pipe 16 is carried up the outside of said casing 29 and 80 bent horizontally thereover to communicate with the bore of a screw-plug 17, the latter inserted in a casting 27 to communicate with an inner tube 18, the latter being open at the top to deliver into an inverted glass receptacle or chamber 20 mounted on said casting and held by means of a clamping-disk 85 21 and the bolts 25. The casting 27 has a transversely extended basal portion projecting equally on opposite sides of the 90 chamber 20 and whose cylindrical cavity 22 is in communication with said chamber by means of a passage 26. The elongated part of said casting has in its bottom near each end an orifice in which is seated a plug 23 95 centrally perforated to deliver through an orificed tip 24, so that oil is dropped from the tips directly upon the bearings of the cranks on the shaft 30. Drippings from said cranks fall into the reserve of oil in the bottom of the casing to be used repeatedly.

The cam-shaft is rotated by means not shown operated by the engine, and the cam-wheel thereon actuates said rock-lever and pump piston to constantly and positively 105 feed the lubricating chamber 20, whence the oil is distributed equally by means of the channels 26, 22 and the tips 24.

This lubricating device is especially adapted for use on the engines of tractors, since the working of the oil as pumped and delivered from the upright tube 18 into the glass chamber 20 may be seen by the operator. The means shown are illustrative of the principle of my invention, which however I do not intend to confine to the precise elements shown, since the same may be varied without departing from the principles of the invention.

Having described my invention, what I claim as new, and desire to secure by Letters Patent, is:

15 1. A lubricating device, comprising a crank-casing pump-cylinder in the bottom of the crank-casing and in communication with a supply of lubricant, a piston reciprocatory in said cylinder, a receptacle above 20 the crank-casing and in communication with said cylinder, a check-valve adapted to control the communication of said cylinder with said supply of lubricant, and horizontally channelled distributing-means in 25 communication with said receptacle and at each end with said crank-casing.

2. A lubricating device, comprising a pump-cylinder in communication with a supply of lubricant, a reciprocatory piston 30 in said cylinder, a check-valve in said cylinder adapted to control its communication with said supply of lubricant, a vessel supported on a higher level than said pump, an open tube leading into said vessel, means of 35 communication between said pump-cylinder and said tube, a channelled distributing device having equal area distributing nipples at opposite ends, and means of communication between said vessel and said distributing 40 device.

3. A lubricating device, comprising a cam-wheel, a pivoted rock-lever actuated by said cam-wheel, a cylinder in communication

with a supply of lubricant, a piston in said cylinder, operative connections between said 45 rock-lever and said piston, a check-valve in the communications of said cylinder with said supply of lubricant, a distributing device for lubricant in communication with said cylinder, and means for controlling the 50 communication between said cylinder and said distributing-device.

4. A lubricating device, comprising a casing containing a supply of lubricant, a pump-cylinder in said casing in communication with said lubricant, a check-valve in the communications of said cylinder with said lubricant, a cam-wheel in said casing, a medially-pivoted rock-lever having one end contacting with said cam-wheel operatively, 55 operative connections between the other arm of said rock-lever and said piston including yieldable resilient means adapted to retain said lever in working contact with said cam-wheel, a transparent closed top vessel supported above said casing, an open-top tube leading upwardly into said vessel, means of communication between said pump-cylinder and the lower end of said tube, a check-valve 60 in said communications, a relatively long 65 horizontal distributing chamber mounted on said casing, said casing being orificed, like nozzles depending from said distributing device through the said orifices and being in communication with opposite ends of said 70 device, and a conduit leading from said transparent vessel into the middle part of the finer hollow of said distributing device.

Signed at Waterloo, Iowa, this 30th day 80 of June, 1915.

LOUIS W. WITRY.
